Primary Examiner — Ian Simmons*Assistant Examiner* — Keith Frank(74) *Attorney, Agent, or Firm* — Warner Norcross & Judd LLP(57) **CLAIM**

We claim a personal care product container, as shown and described.

DESCRIPTION

FIG. 1 is a perspective view of the personal care product container embodying the new design;

FIG. 2 is a left side view thereof;

FIG. 3 is a right side view thereof;

FIG. 4 is a front view thereof;

FIG. 5 is a rear view thereof;

FIG. 6 is a top view thereof; and,

FIG. 7 is a bottom view thereof.

The oblique line shading in FIGS. 1 and 6 is included to indicate a transparent surface. The broken line shading in FIG. 7 forms no part of the claimed design.

1 Claim, 5 Drawing Sheets(56)
